JOHN FRANCIS McNEIL, OF CLIFTON, ARIZONA.

CONCENTRATING-TABLE.

1,368,815.

Specification of Letters Patent. Patented Feb. 15, 1921.

Application filed July 23, 1919. Serial No. 312,770.

To all whom it may concern:

Be it known that I, JOHN F. McNEIL, a citizen of the United States, and a resident of Clifton, in the county of Greenlee and State of Arizona, have invented a new and Improved Concentrating-Table, of which the following is a description.

My invention relates to concentrating tables and while more particularly intended for wet concentration, it can be employed in dry concentration. The invention resides in the system of arranging the riffles and particularly in a bank riffle and its relation to the remaining riffles.

The invention resides further in the arrangement of a feed disposed at the end of the table opposite the discharge as distinguished from a feed arranged along a side of the table, the feed crossing a portion of my novel system of riffles also, as will hereinafter more clearly appear.

The characteristics of my improved riffle system and feed produce certain distinctive advantages and results among which are the following: Better results in savings are obtained as well as cleaner concentrates and more tonnage per table, while there are less repairs, less labor and power required for the operation, and a less number of tables are required for handling a given amount of material on account of the increased tonnage handled per table. Furthermore, the installation does not cost more than systems involving other riffles; the invention may be embodied in standard tables and with a standard stock riffle except in the case of my bank riffle, and the feed means coacting with the novel riffle system insures the distribution of the feed to utilize all the riffles and the entire surface and length of table. Again, the arrangement of riffles is such that a table of ordinary dimensions and standard make is made to constitute in effect two separate and distinct tables in the variation of the riffles and for the successive treatment of the material.

Reference is to be had to the accompanying drawings forming a part of this specification, it being understood that the drawings are merely illustrative of one example of the invention.

Figure 1 is a plan view of a concentrating table embodying my invention;

Fig. 2 is a transverse section on the line 53 2-2, Fig. 1;

Fig. 3 is a perspective view of my bank riffle;

Fig. 4 is a perspective view of one of the riffles in the second series provided on the table.

The table A may generally be of any approved form and supported in any suitable manner, to give it the proper inclination to dispose the head 12 slightly above the discharge end 13 for the concentrates as well as to dispose one side of the table higher than the other to cause the tailings C to flow to and over the lower side, there being indicated conventionally portions of hangers B, Fig. 2. I provide feed means adjacent to the head 12 and transversely of the table, the same being in the form of an elongated distributing box 15 provided with a hopper 14 for receiving the material to be treated. The numeral 17 indicates the lower side over which the tailings pass.

An important feature of my invention consists in a bank riffle 18 and this I dispose oblique to the longitudinal axis of the table and extending from or adjacent to the head 12 obliquely toward the higher side of the table. I arrange riffles at both sides of the bank riffle 18 and of less height than the surface of the table, the two series of riffles being indicated respectively by the numerals 10 and 11. The riffles 10 are disposed parallel to the bank riffle 18 and therefore incline upwardly toward the higher side of the table. Those riffles, however, nearer the center of the table will have sufficient length to terminate a material distance from the higher side of the table, thereby allowing ample clearance for the escape of the concentrates and any sand remaining therewith, from between the riffles. The series of riffles 11 instead of having the obliquity of the riffles 10 are disposed parallel with the longitudinal axis of the table. It will be observed that the feed device 15 extends across more or less of the riffles 10. The position of the feed and the relation of the same to the riffles insure an effective distribution of the material over the table. The top surface 20 of the bank riffle slopes toward the second series 11 to facilitate the flow of the material over the bank riffle to prevent accumulation on said top surface.

The bank riffle and the others are in practice secured by screws or other suitable fastening means, the numeral 19 indicat-

ing holes through which the fasteners are passed. The bank riffle as well as those of the two series are of gradually reduced height toward the discharge end.

5 The box 15 of the feed device has a longitudinal series of holes 21 in a side thereof through which the material may escape and advantageously also, an end escape hole 22. In order that the feed device may be adjusted so that the receiving end or hopper may be higher, to a greater or less extent, than the opposite end depending on the nature of the material being treated, I provide 10 adjusting means. The hopper end of the box may be supported in any suitable manner, there being shown as indicating one means, a cleat 23 thereon resting on a ledge 24 rigid with the table. The feed device is free to be tilted more or less, the opposite 15 end from the hopper being adjustably held by a clamp device including a clamp bolt 25 and nut 26 thereon, the bolt passing through the head 12 and having a bent or hooked end 27 embracing the far side of the 20 box from the head 12, there being a block 28 on the shank of the bolt between the box 15 and the head 12 so that a tightening of the nut 26 will cause the box to be firmly clamped between the hook 27 and the block 25 and hold the box in a given adjustment.

25 There may be two or three of the oblique riffles 10 between the bank riffle 18 and the riffles 11 to insure a wide distribution of the material to the latter riffles by reason of the angular relation thereto of the oblique riffle.

30 With the described arrangement, the bank riffle forms a "pond" between said bank riffle and that side of the table opposite the tailings discharge, adjacent the head 12 or the feed end of the table. Also, the two series of riffles 10, 11 have their rear ends adjacent to the head 12 or feed end of the table and therefore adjacent to the transverse 35 plane of the feed means 14, 15. Thus, the feed to the first series of riffles 10 is directly to said riffles from the feed means near the rear ends of said riffles 10 and similarly, the feed to the second series of riffles 11 by over- 40 flow from the first series 10 and over bank riffle 18, begins adjacent to the rear ends of said riffles 11. Thereby, the concentrating action of all the riffles begins adjacent to their rear ends and adjacent to the head 12 or rear end of the table, thus giving the 45 maximum results in the concentrating action. The obliquity of the bank riffle and the riffles 10 with the forming of the pond by said bank riffle is particularly effective in 50 preventing loss of mineral product by retarding the travel thereof toward the tailing discharge and permitting the mineral product to settle and preventing it from passing over the bank riffle with the tailings. 55 The sloping of the top surface of the

bank riffle toward the parallel riffles 11 prevents the clinging of heavy feed or foreign particles and prevents the formation of slimes on the top surface. A further important result is that I prevent the water in 70 passing over the bank riffle from becoming rippled and agitated which would seriously affect the concentrating action. In the operation of ordinary concentrating tables a very material loss of mineral products occurs adjacent to the medial line of the table by the carrying off of concentrates due to the activities that the water, waste material, and mineral products undergo by the time they reach the medial line of the table coupled with the fact that the depressions in 75 the region referred to contain a large amount of concentrates. With my construction most of the coarse mineral is caught by the first series of riffles 10 and the bank riffle 18 due to the fact that they extend obliquely away from the tailings discharge 17 and by the time the mineral reaches the bank riffle and after it has had ample time and has been subjected to proper conditions for it to 80 have settled on the bottom of the table, it cannot pass over the bank riffle but must travel up an incline to the upper tapered end of the bank riffle and on toward the discharge end 13 for the concentrates. Thus 85 the concentrates discharging at the end of the bank riffle cannot return to the waste product or tailings. Any fine mineral passing over the bank riffle 18 is first subjected to the small series of said inclined riffles between 90 said bank riffle and the riffles 11. The concentrates discharging at the end of the bank riffle cannot return to the waste product or tailings. Any fine mineral passing over the bank riffle 18 is first subjected to the small series of said inclined riffles between 95 said bank riffle and the riffles 11. The parallel riffles 11 are effective in practice in causing the settling of fine mineral particles passing over the oblique riffles causing the same to travel longitudinally of 100 the table to the concentrate discharge end almost without loss. The employment of the series of riffles 11 parallel with the longitudinal axis of the table after treatment of the material by the oblique riffles enables 105 me to obtain a very clean mineral product, said riffles 11 resulting in minimizing the travel of waste product with the remaining concentrates toward the end 13, said waste material flowing over the parallel riffles 11 to the waste or tailings side 17 of the table. 110

115 I would state in conclusion that while the illustrated example constitutes a practical embodiment of my invention, I do not limit myself strictly to the mechanical details herein illustrated, since manifestly the same can be considerably varied without departure from the spirit of the invention as defined in the appended claims.

120 Having thus described my invention, I claim as new and desire to secure by Letters Patent:

1. A concentrating table having one longitudinal side lower than the other for the discharge of tailings, one end of said table 125

- constituting the discharge for the concentrates, feed means at the opposite end of the table to deliver the material to be treated, a series of riffles disposed over that portion 5 of the table adjacent to the higher side and extending from the feed end of the table longitudinally of the latter, and disposed obliquely to incline upwardly toward the higher side, those riffles of said series disposed increasing distances from the higher side of the table being of successively increased length so that the riffles of the series 10 terminate on a transverse line drawn obliquely to the higher side, a second series of 15 riffles between the first series of riffles and said lower side of the table and parallel with said side, and a bank riffle disposed longitudinally of the table parallel with the riffles of the first-mentioned series and adjacent to 20 those riffles of said first series near the second series, said bank riffle and the riffles of the two series being of gradually reduced height toward the discharge end of the table and the top surface of said bank riffle sloping 25 transversely toward the lower side of the table.
2. A concentrating table having one longitudinal side lower than the other for the discharge of tailings, one end of said table constituting the discharge for the concentrates, feed means transversely disposed at the opposite end of the table to deliver the material to be treated, a series of riffles disposed 30 obliquely over that portion of the table adjacent to the higher side, to incline upwardly toward the higher side, those riffles of said series disposed increasing distances from the higher side of the table successively increasing in length, and a second series of 35 riffles on said table nearer the lower side of the table than the first series of riffles and approximately parallel with said lower side, said feed means being adjacent to the first-mentioned series of riffles, and both 40 series of riffles emanating from points directly adjacent to the feed end of the table and adjacent to the transverse line on which the feed means is disposed so that the first 45 series of riffles directly receive the feed at their rear ends and the riffles of the second series receive material adjacent to their rear ends as it overflows transversely from the first series of riffles.
- 50 3. A concentrating table having one longitudinal side lower than the other for the discharge of tailings, one end of said table constituting a discharge for the concentrates, feed means at the opposite end of the 55 table adjacent to the higher side thereof to deliver the material to be treated, a bank riffle extending from the feed end of the table longitudinally of the latter and disposed obliquely to incline upwardly toward the 60 higher side, the top surface of said bank riffle sloping transversely to present a dip toward the lower side of the table, riffles between said bank riffle and the higher side of the table, and riffles on the table between 65 said bank riffle and lower side of the table,
- said bank riffle rising higher from the table than the other riffles, and all of said riffles ranging generally lengthwise of the table from the feed end thereof in the general direction of the discharge for the concentrates. 70
4. A concentrating table, one end of which constitutes a discharge for the concentrates and one side of which constitutes a discharge for the tailings, feed means positioned to deliver material to the table adjacent to that end opposite the discharge of the concentrates, a bank riffle extending generally longitudinally of the table from the feed end thereof toward the opposite end, and presenting a top surface sloping transversely 75 to present a dip toward the side at which the tailings are discharged, and riffles at each side of the bank riffle, said last mentioned riffles having their top surfaces in a single plane parallel with the table surface 80 and ranging longitudinally of the table from the feed end thereof.
5. A concentrating table having one longitudinal side lower than the other for the discharge of tailings, one end of said table constituting the discharge for the concentrates, feed means transversely disposed at the opposite end of the table to deliver the material to be treated, a series of riffles disposed 85 obliquely over that portion of the table adjacent to the higher side, to incline upwardly toward the higher side, those riffles of said series disposed increasing distances from the higher side of the table 90 successively increasing in length, and a second series of riffles on said table nearer the lower side of the table than the first series of riffles and approximately parallel with said lower side, said feed means being adjacent to the first-mentioned series of riffles, and both 95 series of riffles emanating from points directly adjacent to the feed end of the table and adjacent to the transverse line on which the feed means is disposed so that the first series of riffles directly receive the feed at 100 their rear ends and the riffles of the second series receive material adjacent to their rear ends as it overflows transversely from the first series of riffles.
6. A concentrating table, one longitudinal 105 side of which constitutes a discharge for the tailings and one end of which constitutes a discharge for the concentrates, feed means transversely disposed at the other end of the table to deliver material to be treated, 110 and riffles on said table, those riffles nearest the side of the table opposite the tailings discharge extending obliquely toward said opposite side, those of the oblique riffles which are disposed increasing distances 115 from said opposite side being successively of increased lengths, and there being riffles between said oblique riffles and that side of the table constituting the tailings discharge 120 and extending substantially from end to 125 end.
7. A concentrating table, one longitudinal side of which constitutes a discharge for the tailings and one end of which constitutes a discharge for the concentrates, feed means transversely disposed at the other end of the table to deliver material to be treated, 130 and riffles on said table, those riffles nearest the side of the table opposite the tailings discharge extending obliquely toward said opposite side, those of the oblique riffles which are disposed increasing distances from said opposite side being successively of increased lengths, and there being riffles between said oblique riffles and that side of the table constituting the tailings discharge and extending substantially from end to 130 end.

end of the table, said feed means being adjacent to the first-mentioned series of riffles, and both series of riffles emanating from points directly adjacent to the feed end of the table and adjacent to the transverse line on which the feed means is disposed so that the first series of riffles directly receive the feed at their rear ends and the riffles of the second series receive material adjacent to their rear ends as it overflows transversely from the first series of riffles.

7. A concentrating table, one longitudinal side of which constitutes a discharge for the tailings and one end of which constitutes a discharge for the concentrates, feed means at the opposite end of the table and adjacent to the opposite side from the first mentioned side to deliver the material to be treated, a bank riffle extending from adjacent the feed end of the table obliquely toward said opposite side, riffles between said bank riffle and said opposite side of the table and extending obliquely toward said opposite side from the feed end, and riffles at an angle to the other riffles and disposed between the bank riffle and the first-mentioned side of the table, said bank riffle rising higher from the table than the other riffles, said feed means being adjacent to the first-mentioned series of riffles, and both series of riffles emanating from points directly adjacent to the feed end of the table and adjacent to the transverse line on which the feed means is disposed so that the first series of riffles directly receive the feed at their rear ends and the riffles of the second series receive material adjacent to their rear ends as it overflows transversely from the first series of riffles.

40 8. A concentrating table, one longitudinal side of which constitutes a discharge for the tailings and one end of which constitutes a discharge for the concentrates, feed means transversely disposed adjacent to the opposite end of the table and adjacent to the opposite side from the first-mentioned side to deliver the material to be treated, a bank riffle extending from adjacent the feed end of the table obliquely toward said opposite side, the top surface of said bank riffle sloping transversely to present a dip toward the first-mentioned side of the table, a series of riffles between said bank riffle and the first-mentioned side of the table, and a series of 55 riffles between said bank riffle and said opposite side of the table, the two series of riffles having their top surfaces in a single plane parallel with the table surface; said feed means being adjacent to the first-mentioned series of riffles, and both series of riffles emanating from points directly adjacent to the feed end of the table and adjacent to the transverse line on which the feed means is disposed so that the first series of 60 riffles directly receive the feed at their rear

ends and the riffles of the second series receive material adjacent to their rear ends as it overflows transversely from the first series of riffles.

9. A concentrating table, one longitudinal side of which constitutes a discharge for the tailings and one end of which constitutes a discharge for the concentrates, feed means adjacent to the opposite end of the table and adjacent to the opposite side from the first-mentioned side to deliver the material to be treated, a bank riffle extending from adjacent the feed end of the table obliquely toward said opposite side, a series of riffles disposed between the bank riffle and said opposite side of the table approximately parallel with said bank riffle, and a series of riffles disposed on the table between the bank riffle and the first-mentioned side of the table and parallel with the latter side, the top surface of said bank riffle sloping transversely to present a dip toward the first-mentioned side of the table.

10. A concentrating table, one longitudinal side of which constitutes a discharge for the tailings and one end of which constitutes a discharge for the concentrates, feed means adjacent to the opposite end of the table and adjacent to the opposite side from the first-mentioned side to deliver the material to be treated, a bank riffle extending from adjacent the feed end of the table obliquely toward said opposite side, a series of riffles disposed between the bank riffle and said opposite side of the table approximately parallel with said bank riffle, and a series of riffles disposed on the table between the bank riffle and the first-mentioned side of the table and parallel with the latter side, the top surface of said bank riffle sloping transversely to present a dip toward the first-mentioned side of the table, said feed means being adjacent to the first-mentioned series of riffles, and both series of riffles emanating from points directly adjacent to the feed end of the table and adjacent to the transverse line on which the feed means is disposed so that the first series of riffles directly receive the feed at their rear ends and the riffles of the second series receive material adjacent to their rear ends as it overflows transversely from the first series of riffles.

11. A concentrating table, one longitudinal side of which constitutes a discharge for the tailings and one end of which constitutes a discharge for the concentrates, feed means transversely disposed at the opposite end of the table and adjacent to the opposite side from the first-mentioned side to deliver the material to be treated, a bank riffle extending from adjacent the feed end of the table obliquely toward said opposite side, riffles between said bank riffle and said opposite side of the table and extending obliquely toward said opposite side from 120 125 130

the feed end, and riffles at an angle to the other riffles and disposed between the bank riffles and the first-mentioned side of the table, said bank riffle rising higher from the 5 table than the other riffles, the bank riffle and riffles at each side thereof being of reduced height from the feed end of the table, said feed means being adjacent to the first-mentioned series of riffles, and both series of 10 riffles emanating from points directly adjacent to the feed end of the table and adjacent to the transverse line on which the feed means is disposed so that the first series of riffles directly receive the feed at their 15 rear ends and the riffles of the second series receive material adjacent to their rear ends as it overflows transversely from the first series of riffles.

12. A concentrating table of which one 20 longitudinal side constitutes the discharge for the tailings and one end of the table constitutes a discharge for the concentrates, feed means transversely disposed adjacent to that end of the table opposite to the discharge 25 end, a series of riffles disposed over that portion of the table near the opposite side from the tailings discharge and extending obliquely from adjacent the end of the table opposite the concentrates discharge toward 30 said opposite side; together with a bank riffle substantially parallel with said first-mentioned riffles, and riffles between said bank riffle and the tailings discharge of the table, said last-mentioned riffles being 35 substantially parallel with the longitudinal axis of the table, said feed means being adjacent to the first-mentioned series of riffles, and both series of riffles emanating from points directly adjacent to the feed end of 40 the table and adjacent to the transverse line on which the feed means is disposed so that

the first series of riffles directly receive the feed at their rear ends and the riffles of the second series receive material adjacent to their rear ends as it overflows transversely 45 from the first series of riffles.

13. A concentrating table of which one longitudinal side constitutes the discharge for the tailings and one end of the table constitutes a discharge for the concentrates, a 50 series of riffles disposed over that portion of the table near the opposite side from the tailings discharge and extending obliquely from adjacent the end of the table opposite the concentrates discharge toward said opposite side; together with a bank riffle substantially parallel with said first-mentioned riffles, and riffles between said bank riffle and the tailings discharge of the table, said bank 55 riffle having a top surface sloping toward the tailings discharge side of the table.

14. A concentrating table having one longitudinal side lower than the other for the discharge of tailings, one end of said table constituting a discharge for the concentrates, 65 feed means at the opposite end of the table adjacent to the higher side thereof to deliver the material to be treated, a bank riffle extending from the feed end of the table longitudinally of the table and disposed 70 obliquely to incline upwardly toward the higher side, riffles between said bank riffle and the higher side of the table, and riffles on the table between said bank riffle and the lower side of the table, said bank riffle rising 75 higher from the table than the other riffles and all of said riffles ranging generally lengthwise of the table from the feed end thereof in the general direction of the discharge for the concentrates.

JOHN FRANCIS McNEIL.
